UNITED STATES PATENT OFFICE

2,585,311

HECTOGRAPHIC COPYING DEVICE

Donald N. Grundberg, Stoneham, Mass.

Application February 18, 1950, Serial No. 145,033

2 Claims. (Cl. 101—131)

1

My present invention relates to copying devices, and more particularly to a copying device including a holder adapted to be held in the hand of the user, and by means of which typewritten, hand written, drawn, and like prepared matter, impressed on a master paper in mirror or reverse image, may be utilized to produce a plurality of copies on a card or paper of a size adapted to be held on a base or platen, by the spirit duplication process using an alcohol base fluid.

My present invention further relates to an improved hand operated copying device in which a bed or platen is provided with means for registering and holding a card or sheet of paper in correct position to be engaged during the copying operation by a master paper carrying matter in reverse or image form, by a holder held in the hand of the operator, and contacting with the card or sheet of paper by a combined pressing and rocking action.

An object of my invention is an improved hand operated copying device.

Another object of an improved hand operated device for producing duplicate copies by means of the spirit duplication process using an alcohol base fluid.

Another object is an improved hand operated holder provided with a reservoir for holding a supply of base fluid, and having a fluid distributing roller associated therewith, together with a rocking member carrying a master paper having matter to be duplicated impressed thereon in mirror, or reverse form.

A further object is an improved hand operated holder adapted for association, and in combination with an improved base or platen having means thereon for correctly positioning, registering, and holding the paper to receive the impression from the master paper, and for correctly preliminarily positioning the holder prior to the copying operation.

Other objects and novel features of the construction and arrangement of parts comprising the device will appear as the description of the invention progresses.

A still further object of the invention is an improved hand operated device for producing duplicate copies from matter impressed in mirror, or reverse image form from an aniline, or other suitable, dye carbon.

In the accompanying drawings:

Figure 1 is a top plan view of the lower member of the master sheet holder, taken on the line 1—1 of Figure 2, and with one end of the fluid applying roller shown in section.

2

Figure 2 is a vertical sectional side view, taken on line 2—2 of Figure 1, and with the top member having a fluid holding chamber, or reservoir, formed therein, mounted in position on the lower member.

Figure 3 is an elevational view, looking to the right in Figure 2, and showing, in section taken approximately on the line 3—3 of Figure 2, the means for locking the members of the master sheet holder in closed, or operative, position with respect to each other.

Figure 4 is a sectional view, on an enlarged scale, taken on the line 4—4 of Figure 1, and showing the connection between the fluid holding chamber and the liquid dispensing roller.

Figure 5 is a plan view of the base or platen.

Figure 6 is a side elevational view of the device shown in Figure 5.

Figure 7 is an enlarged sectional view, taken on the line 7—7 of Figure 5, and showing the paper clamping device, and the means for correctly positioning the sheet of paper, or other material, on the base or platen.

Figure 8 is a view, similar to Figure 7, but showing the sheet holding means in holding or locked position.

Figure 9 is a perspective view of the complete device, with a master sheet holder resting on the top surface of the base or platen, and

Figure 10 is a schematic view to illustrate the mode of operating the device.

Referring to the drawings, and particularly to Figures 1 to 4 inclusive, 10 designates a holder, adapted to be held in and operated by one hand of an operator. This holder is comprised of an upper half and a lower half 11 and 12 respectively. Both halves 11 and 12 are substantially rectangular, as viewed in plan, and are hinged together at one end by a shaft 13, and are adapted to be folded into position, as shown in Figure 2 to form a closed unit, the upper and lower faces 14 and 15 respectively of which are rounded to permit the holder to be rocked back and forth on a plane surface.

45 Preferably the halves 11 and 12 are made by stamping from sheet metal of appropriate thickness, and at the meeting edges of the halves, adjacent the end remote from the shaft 13 are provided with interlocking members 16. The meeting edges of the halves 11 and 12 between the locking members 16 and the shaft 13 are cut away, as indicated by the numeral 17, to thus provide a better holding surface for holding the device in the hand of the operator.

55 Within the upper half 11 is a diaphragm 18

defining, with the upper half, a reservoir 19 in which is placed a filling of absorbent cotton or other suitable material. The diaphragm 18 is provided with a filling hole 20 normally closed by a stopper or plug 21, which may be removed at will to allow entrance of a supply of alcohol base fluid. The end of the diaphragm is formed to define a substantially inverted U-shaped channel 22, spaced from and partially encircling a base fluid distributing roller 23 freely rotatable on the shaft 13 and extending the width of the holder upper half 11.

In the inverted U-shaped channel 22 is formed a perforation 24 which communicates with the interior of the reservoir 19, and this perforation may be round or elongated as a slot, and of a suitable size to permit adequate flow of the alcohol base fluid to the interior of the inverted U-shaped channel 22. Also the channel 22 houses a strip of felt 25, the outer surface of which engages with the alcohol base fluid distributing roller 23 at all times. The perforation 24 is filled with absorbent cotton or other like suitable material, so that there is an absorbent connection between the absorbent material in the reservoir 19 and the felt strip 25 at all times. There is therefore, a flow of alcohol base fluid to the fluid distributing roller at all times during the rotation of such roller.

As stated above, the outer, or lower surface of the lower half 12 of the holder element, as viewed in Figure 2, is rounded, so as to make it possible to allow a rolling or rocking motion to the holder during the copying operation. Referring to said Figure 2, there is provided, in the lower half 12, adjacent the base fluid distributing roller 23, a plate 26, the ends of which are secured to the side walls of said lower half 12. The plate 26, throughout its length, has its lower surface—as viewed in Figures 2 and 4—spaced apart from the end of the arcuate bottom of the lower half 12 to define a narrow slot 27 through which may be slid, or forced, one end 28 of a master paper 29 which has impressed thereon in mirror image the matter to be duplicated or copied, it being understood that such matter is exposed to view when the master paper is placed as above described.

The paper 29, after the end 28 is positioned in the slot 27, is folded over onto the lower rounded surface of the lower half 12 and the end 30 is folded over the forward edge 31 of the arcuate bottom of the lower half 12. To facilitate holding the master paper 29 in position until the interlocking members 16 are brought together, I provide an opening 32 in the upper half 11 to permit the entrance of the finger of the operator to hold the master paper 29 in position.

Referring now to Figures 5 to 8 inclusive, 33 designates a base or platen, preferably rectangular in form, and at its right hand end, as viewed in Figures 5 and 6, is a stop 34 perpendicular to the length of the base or platen. This stop may be made integral with the base or platen 33, or may be made separate from and secured to the upper surface of the base or platen in any desired manner. At the opposite, or left hand end, of the upper face of the base or platen 33 is secured, as by the screws 35, a plate 36 of spring material, the free edge of which engages the left end of a card or sheet of paper 37 on which matter is to be impressed by the characters on the exposed surface of the master paper 29 carried by the holder above described. The width of the plate 36, between the free edge thereof and the screws 35, is greater than one-half the circumference of

the roller 23 in order to ensure a feed of base fluid before it engages with the card or paper 37.

The upper surface of the base or platen 33, beneath the spring plate 36 and parallel to the stop 34 is provided with a groove 38, substantially rectangular in cross-section. In this groove 38 is a bar 39, one end 40 of which extends upwardly and then rearwardly, or to the left, as viewed in Figures 5 to 8 inclusive. To correctly position the card or sheet of paper 37, the extending end 40 is depressed—see Figure 7—thus lifting the free edge of the spring plate 36 and permitting the edge of the card or paper 37 to be pushed under the free edge of the spring plate 36 and into engagement with the bar 39. When thus positioned the extending end 40 is released—see Figure 8—whereupon the free end of the spring plate 36 clamps the edge of the card or paper 37 in position on the upper surface of the base or platen 33.

Assuming the various parts of the device have been assembled as above described, and that a card or sheet of paper is in position on the upper surface of the base or platen 33, the method of operation will be clear from the showing in Figure 10.

The operator grasps the holder by the upper half 11 and momentarily rests the distributor roller 23 on the spring plate 36 as to line up the holder with respect to the card or paper and the base or platen 33. At this time the holder is in the position A and is to be moved in the direction of the adjacent arrow. While thus held in an upright or slightly tilted position, the holder is drawn along the card or paper 37, and the fluid distributing roller distributes a coating of liquid on the upper expose surface of the card or paper 37. This movement is continued until the holder engages with the stop 34 at the opposite end of the base or platen, whereupon the holder is lined up with and in correct position to print. The operator then rotates the holder on the roller 23, as indicated by the arrow B and with a rocking movement, as indicated by the arrows on the part 12, presses the master paper on such segment on the card or paper 37, thus transferring and printing the matter on the master paper onto the card or paper 37.

This operation may be repeated indefinitely and rapidly, or as long as the supply of alcohol base liquid holds out, and, or, the supply of aniline dye lasts on the master sheet, or as desired.

What I claim is:

1. An improved copying device including a holder adapted to be held in the hand of an operator, said holder comprising a lower portion and an upper portion hingedly mounted together at one end on a transverse shaft, said upper and lower portions being substantially rectangular in form and hollow, the upper face of the upper portion and the lower face of the lower portion being arcuate in form, a liquid distributing roller rotatably mounted on a transverse shaft at the junction of the upper and lower portions, means on the lower portion for removably securing a master sheet of material on which may be impressed, with an aniline dye composition, characters to be copied, a reservoir in the upper portion for holding a supply of alcohol solution, and means extending from the reservoir to the liquid distributing roller for feeding a supply of alcohol liquid to said roller as the roller is rotated.

2. An improved copying device including a holder adapted to be held in the hand of an operator, said holder comprising a lower portion and an upper portion, hingedly mounted together at one end on a transverse shaft, said upper and lower portions being substantially rectangular in form and hollow, the upper face of the upper portion and the lower face of the lower portion being arcuate in form, a liquid distributing roller rotatably mounted on a transverse shaft at the junction of the upper and lower portions, means on the lower portion for removably securing a master sheet of material on which may be impressed, with an aniline dye composition, characters to be copied, a reservoir in the upper portion for holding a supply of an alcohol solution, and absorbent means extending from the reservoir to the liquid distributing

roller for feeding a supply of alcoholic liquid to said roller, as said roller is rotated.

DONALD N. GRUNDBERG.
